LETTER OPENER

Carmen D. Pancari, Bellmawr, N. J.

Application July 25, 1957, Serial No. 47,088

Term of patent 14 years

(Cl. D74—1)

The essential features of the design reside in the portions shown in solid lines on the drawing.

I claim:

The ornamental design for a letter opener, as shown and described.
